Joseph L. Levy

UNITED STATES PATENT OFFICE.

CHARLES H. TOWNSEND, OF YONKERS, NEW YORK.

SPRINKLER-HEAD FOR FIRE-EXTINGUISHING SYSTEMS.

1,261,873.

Specification of Letters Patent. Patented Apr. 9, 1918.

Application filed February 1, 1917. Serial No. 145,844.

To all whom it may concern:

Be it known that I, CHARLES H. TOWNSEND, a citizen of the United States, and a resident of the city of Yonkers, county of Westchester, and State of New York, have invented certain new and useful Improvements in Sprinkler-Heads for Fire-Extinguishing Systems, of which the following is a specification.

This invention relates to the type of sprinkler head for fire extinguishing systems wherein the valve is normally held to its seat by means interposed between it and the yoke, the valve retaining means being caused to move out of engagement with said valve by the heat of the fire.

The primary object of this invention is to provide a device of this character of simple construction involving a minimum of parts and material, with considerable ease in assemblage and which will be positive and certain in operation.

With this object in view, I have devised the construction shown in the accompanying drawing forming part hereof and more particularly pointed out in the specification and claim hereto attached.

Reference is to be had to the accompanying drawing, in which—

Fig. 1 is a side elevation, partly in section, of the sprinkler head;

Fig. 2 is a perspective view of the plate which holds the valve on its seat;

Fig. 3 is a perspective view of the upper plate;

Fig. 4 is a perspective view of the locking plate;

Fig. 5 is a vertical sectional view through the valve retaining means;

Fig. 6 is a front elevation of said valve retaining means;

Fig. 7 is a rear elevation of the same; and

Figs. 8 and 9 are diagrammatic views indicating the manner in which the parts of the valve retaining means separate to allow the opening of the valve.

Throughout the various views of the drawings, similar reference characters designate similar parts.

In the preferred embodiment of my invention, as indicated in the accompanying drawing, the valve is indicated at 1, said valve being provided with a domed or rounded head in which is a recess 2 constituting a seat for the lower end of the valve retaining mechanism.

A plate 3 is provided with an offset curved lower end 4 and this end 4 is seated in the recess 2 of the valve head. An upper plate 5 interengages the plate 3 and the upper end 6 of this plate 5 is offset and curved and bears against a conical pointed screw 7, secured in the yoke 8. The plates 3 and 5 are each cut away as at 11 and 15 and the thin portions of these plates overlap so that when the two plates are thus placed together they form a structure of uniform thickness.

The upper plate 5 is provided with an opening 14 and the lower plate 3 is provided with a lip 13 which is positioned opposite said opening, as indicated in Figs. 5, 6 and 7.

The locking plate 9 is provided with a laterally extending, upwardly turned lip 10, and said lip 10 passes through the opening 14 in the position shown in Figs. 5, 6 and 7.

From the foregoing, the operation of my improved device will be readily understood. The parts are assembled in the position shown in Fig. 1, with the plates 3 and 5 overlapping in the manner heretofore described with the lower end of the plate 5 supported on the ledge or shoulder 12 of the plate 3. The locking plate 9 bears against the outer surface of the plate 3 with its lip 10 projecting through the opening 14 in the plate 3. Solder 16 or any other fusible means is placed between the plates whereby a unitary structure is formed. After the parts are soldered together, the structure is placed between the valve and screw 7 by unscrewing said screw and then tightening the same downwardly on the upper end 6 of the plate 5.

When the heat becomes of sufficient intensity, the solder is melted whereby the plates are freed from one another and will begin to move as indicated in Fig. 8, the lip 13 on the plate 3 lifting the locking plate out of engagement with the plate 5 until the parts are finally separated, as shown in Fig. 9, and the valve released.

From the foregoing, it is obvious that my invention is not to be restricted to the exact embodiment herein shown, but is broad enough to cover all structures coming within the scope of the annexed claim.

What I claim is—

In a device of the class described, an upper plate and a lower plate, the upper plate having its upper end bearing against a support, the lower plate having its lower end

resting on top of a valve, both of said plates having thinned portions, said thinned portions overlapping and secured together by a fusible material, the upper plate having 5 an aperture above its thin portion, a locking plate having an off-set projection extending from its upper end and entering said aper-

ture, and fusible material connecting the outer face of the lower plate and the locking plate together.

10

Signed at the city of New York, county of New York, and State of New York, this 18th day of January, 1917.

CHARLES H. TOWNSEND.
